IRRIGATION ROTARY PISTON ACTION PUMP

Herbert L. Johnson, Dodge City, Kans.

Application August 8, 1939, Serial No. 289,034

2 Claims. (Cl. 163—132)

This invention relates to pumps especially adaptable for irrigation and similar work and has for the primary object the provision of a device of this character which will force liquid with a minimum saving in motive power and is so constructed that any of the parts thereof may be readily renewed when worn and which embodies a construction which will be durable and efficient and may be manufactured and sold at a low cost.

With these and other objects in view, this invention consists in certain novel features of construction, combination and arrangement of parts to be hereinafter more fully described and claimed.

For a complete understanding of my invention, reference is to be had to the following description and accompanying drawing, in which

Figure 1 is a side elevation partly in section illustrating a pump constructed in accordance with my invention and having the cover plate thereof removed.

Figure 2 is a sectional view taken on line 2—2 of Figure 1.

Figure 3 is a transverse sectional view taken on line 3—3 of Figure 1.

Referring in detail to the drawing, the numeral 1 indicates a pump housing having therein a piston chamber 2 which, horizontally, is rectangular, but, vertically, is of elongated, substantially elliptical shape and communicating with said chamber are passages 3 and 4. Either of these passages may form the inlet or the outlet for the pump depending in which direction the pump is driven. For convenience of description the passage 3 will be termed the inlet and the passage 4 the outlet. The housing has the passages 3 and 4 separated by an abutment 5 in which is provided a space 6. The housing includes a removable cover plate 7 providing one of the side walls of the housing while the opposite side wall of the housing is offset adjacent each end of the piston chamber to provide journals 8 and circular recesses 9, and operating in said recesses 9 are discs 10, the pintles 11 thereof being received in the journals 8. A rectangular plate forming a piston 12 is pivoted at its ends crankwise on the discs 10 and has wiping contact at its longitudinal margins with the opposite sides of the piston chamber, and also has alternating wiping contact at its ends with the curved ends of the piston chamber. The plate-like piston intermediate its ends is provided with a rounded, undercut grooved, transverse enlargement providing a journal 13 to receive at one end a crank pin 14

of a drive disc 15 and which also pivotally connects to the plate-like piston a division plate 16 having a round beaded enlargement at one end to fit rotatably in the journal groove. A shaft 15' of the drive disc 15 is journaled in a bearing 17 formed in the removable wall 7 of the housing 1 and has secured thereto a pulley 18 or some other similar medium for applying power to the shaft 15'. The drive disc 15 seats in a recess 10 formed in the removable wall 7 of the housing so that it will not interfere with the motion of the plate-like piston 12. The division plate 16 is slidably received in a slot of a shaft 19 fitted rotatably throughout the major portion of its 15 length in a portion of the abutment 5 which is accordingly slotted (see Figure 1) and the ends of the shaft being received in recessed bearing portions of the housing walls (see Figure 3). The division plate 16 has wiping contact with the 20 opposite sides of the housing and its motion is both oscillatory and longitudinally slidable so as to readily follow the movement of the plate-like piston 12. The plate-like piston due to its cranked mountings will have a motion which may be termed a compound eccentric bar motion.

In operation, the motion of the plate-like piston is towards and from the upper wall A of the piston chamber, also towards and from the curved end walls B of the piston chamber. When the 30 passage 3 is considered as the inlet the discs 10 rotate in the direction indicated by the arrow so that when the left hand end of the plate-like piston moves from the position C successively, first downwardly and longitudinally, to the position D, and thence upwardly and longitudinally to the position E, liquid from the intake 3 is lifted upwardly into the space between the plate-like piston and the top wall A. On continued movement of the left hand end of the plate-like piston from the position E to the position F, the liquid in said space is placed under pressure and forced outwardly around the right hand end of the plate-like piston into the outlet passage 4 under considerable pressure. The separating plate 16 prevents the outgoing liquid under pressure from re-entering the inlet passage 3.

What is claimed is:

1. In a pump, a housing having an elongated piston chamber of generally rectangular form, the opposite end portions of which are semi-cylindrical, and an inlet and a parallel outlet communicable with said chamber near the ends thereof, supporting guides rotatably mounted in the opposite end portions of the said chamber, an elongated platelike piston marginally contiguous

to the opposite side walls of the chamber, said piston having the ends thereof pivotally attached crankwise to said rotatable supporting guides whereby to travel with parallel orbital motion in said chamber, said piston ends during part of such travel being peripherally contiguous to the end portions of said chamber, a driven shaft journaled in said housing, a crank element secured to said shaft whereby to rotate therewith and having a pivotal attachment to said piston intermediate the ends thereof, and a movable dividing plate provided within the housing for separating the inlet and outlet, said dividing plate being pivotally attached at one end to the piston intermediate the ends of the latter and having a mounting on the housing with provision for a combined oscillation and lengthwise reciprocation of said dividing plate in compensation with the parallel orbital motion of the piston.

2. In a pump, a housing having an elongated piston chamber of generally rectangular form, the opposite end portions of which are semi-cylindrical, and an inlet and a parallel outlet communicable with said chamber near the ends thereof, supporting guides rotatably mounted in the opposite end portions of the said chamber, an elongated platelike piston marginally con-

tinguous to the opposite side walls of the chamber, said piston having the ends thereof pivotally attached crankwise to said rotatable supporting guides whereby to travel with parallel orbital motion in said chamber, said piston ends during part of such travel being peripherally contiguous to the end portions of said chamber, a driven shaft journaled in said housing, a crank element secured to said shaft whereby to rotate therewith and having a pivotal attachment to said piston intermediate the ends thereof, and a movable dividing plate provided within the housing for separating the inlet and outlet, said dividing plate being marginally contiguous to the opposite side walls of the housing and pivotally attached at one end to the piston intermediate the ends of the latter, a longitudinally-slotted rockshaft mounted for oscillation in said housing between said inlet and outlet ports, the portion of said dividing plate remote from its end which is attached to the piston and adjacent its opposite end being slidably mounted in said rockshaft, whereby, a combined oscillatory and lengthwise movement is imparted to the dividing plate during the parallel orbital travel of the piston.

HEREERT L. JOHNSON.
